United States Patent Office

Des. 187,700
Patented Apr. 19, 1960

187,700

BOOK RACK

Theodore Sobel, New Rochelle, N.Y., assignor, by mesne assignments, to General Foods Corporation, White Plains, N.Y., a corporation of Delaware

Application May 5, 1959, Serial No. 55,778

Term of patent 14 years

(Cl. D33—2)

FIG. 2.

FIG. 1.

FIG. 4.

FIG. 3.

FIG. 5.

Fig. 1 is a front perspective view of a book rack embodying my design;

Fig. 2 is a perspective view thereof taken from the rear;

Fig. 3 is a side view of the rack shown in Fig. 1;

Fig. 4 is a front perspective view showing the pivotal element extended; and

Fig. 5 is a side elevational view of the rack of Fig. 4.

I claim:

The ornamental design for a book rack, substantially as shown.
